UNITED STATES PATENT OFFICE.

ERNEST ROWLAND HILL, OF EAST ORANGE, NEW JERSEY, ASSIGNOR TO THE WESTINGHOUSE AIR BRAKE COMPANY, OF PITTSBURGH, PENNSYLVANIA, A CORPORATION OF PENNSYLVANIA.

AUTOMATIC TRAIN-STOP.

1,138,216.

Specification of Letters Patent. Patented May 4, 1915.

Application filed February 9, 1911. Serial No. 807,570.

To all whom it may concern:

Be it known that I, ERNEST ROWLAND HILL, a citizen of the United States, residing at East Orange, in the county of Essex and State of New Jersey, have invented certain new and useful Improvements in Automatic Train-Stops, of which the following is a full, clear, and exact description.

In the operation of railways it is desirable to have means whereby under certain circumstances, as for example, in the event of the car or train running past a signal, the car or train may be brought to a stop or have its speed reduced by agencies which are not dependent for operation upon the will of the motorman or engineer. Devices for such purposes are commonly known as automatic train-stops, and usually take the form of a trip device arranged adjacent to the track and associated with the signaling system in such manner that when the signal indicates danger or caution the trip device will be raised into the path of a movable member carried on the train and connected with the controlling instrumentalities thereof so that if the train runs past or fails to heed the signal such movable member, colliding with or engaging the trip device will be actuated and so cut off the power from the train or apply the brakes or perform some other function or functions of like or equivalent nature, singly or combined.

My present invention relates to apparatus of this general type, and its chief object is to provide improved means for the purpose, whereby the desired operations may be performed with certainty and precision.

A further object is to provide means, in conjunction with apparatus of the character indicated whereby the movable controlling member carried by the car or train is protected from contact with objects of any kind in its path except the trip device provided for the purpose, said means serving as a plow or guard to clear snow, ice, and other obstructions from the path of the train-controlling member.

To these and other ends the invention consists in the novel features of construction and combinations of elements hereinafter described, and more particularly set forth in the appended claims.

Convenient and effective embodiments of the invention are illustrated in the accompanying drawings and will now be de-

scribed somewhat in detail, but it should be kept in mind that the invention may be embodied in other forms without departure from its proper spirit and scope.

Referring now to the drawings, Figure 1 is a side view, partly in section, showing the trip device at the instant of engagement by the advancing guard or plow carried by the train. Figs. 2 and 3 are detail side views showing different positions of the trip device as it is passed by the devices carried by the train. Fig. 4 is a front view, partly in section, of the parts shown in Fig. 1. Fig. 5 is a side view showing another form of trip device and another form of air brake valve and valve-operating member. Fig. 6 is a detail side view showing the position of the valve-actuating member and the trip device shortly before the actuation of the valve is completed. Fig. 7 is a front view of the parts shown in Fig. 5.

In the preferred form of the invention the trip device may operate an alarm and control the movement of the car or train through the agency of a suitable switch in an electric control system, or a valve in a pneumatic or electro-pneumatic system; or a valve associated with the air brake system and so connected therewith, for example in the train pipe, that the operation of the valve by the trip device will cause the brakes to be applied.

In the form shown in Figs. 1 to 4 inclusive the valve, designated by 10, is of the slide valve, plunger, or piston type, connected to the train pipe (not shown) by a pipe 11 and having a port 12 for the escape of air when the valve is operated. The depending stem or plunger 13 is provided with a head 14, square in plan, for engagement with the trip device.

The valve is mounted in a supporting frame 15, which is in turn mounted on a suitable part of the car, as for example a longitudinally extending beam 16 carried by or forming part of one of the trucks, not shown. To provide for vertical adjustment of the supporting frame, to bring the valve to the proper position with respect to the trip device, the frame is formed with two arms 17, in front and rear of the valve, having horizontally corrugated faces 18 co-operating with similarly corrugated plates 19 on the side of the supporting member 16. To adjust the frame the bolts 20, extending

through the vertical slots 21 in the arms 17, are loosened and the frame raised or lowered as may be necessary, after which the bolts mentioned are tightened up, thereby binding the frame securely in adjusted position.

Depending from the frame 15 in front and rear of the plunger 13 and head 14 are two rigid guards or plows 22, 23, of suitable form, the purpose of which is to clear obstructions from the path of the piston, one or the other of the guards performing such duty according to the direction in which the car or train is traveling. Of course if the car is always turned around when its direction of travel is reversed, the rear guard may be omitted, but as this is not likely to be the case I prefer to employ two guards, as shown.

The trip device, designated generally by 24, is rigidly mounted on a rock shaft 25 arranged transversely with respect to the track, one rail of which is shown in section at 26. This shaft is connected with the signaling system in such manner, not shown, that when the track ahead is clear the forked stop arm 27 will be depressed to the position indicated in dotted lines in Fig. 1, but when the signal changes to "danger" the arm will be raised to the full line position. Pivoted at the free or outer end of the stop arm is a device comprising a sleeve 28 encircling the pivot 29 and three radial fingers 30, 31, 32, mounted thereon. Inside the sleeve 28 is a coil spring 28^a the ends of which pass through the end-caps 33 on the sleeve and extend into suitable recesses, not shown, in the adjacent faces of the arm 27, the parts named being so proportioned and arranged that the sleeve will be yieldingly held in the position shown in Fig. 1, with the middle finger 31 in alinement with the arm 27. A cap 24 incloses the sleeve, the pivot and the upper ends of the fork, to exclude cinders and the like.

Assume now that the car is moving from right to left, as viewed in Fig. 1, and that the stop arm is raised. The outer fingers 30, 32, being so spaced with respect to the middle finger that the finger 32 will be below the bottom of the forward guard, 22, it will be seen that the last named guard will strike the middle finger and swing the same forwardly, or in the direction of the car's travel, thereby bringing the rear finger 32 up, against the head, 14, of plunger 13 and imparting an upward movement thereto. As the car moves on the guard continues to depress the middle finger until the latter engages the bottom of the guard as in Fig. 2, by which time the rear finger has completed the upward movement of the valve plunger, thereby opening the valve and allowing air to escape from the train-pipe, the valve of course remaining open long

enough to cause the brakes to be applied. The forward swing of the fingers is now continued by the rear guard, in engagement with the rear finger 32, the parts taking the position shown in Fig. 3, in which the finger 32 bears against the bottom of the rear guard. As the car moves on the guard 23 clears the finger 32, whereupon the spring 28^a restores the fingers to the position shown in Fig. 1.

In Figs. 5, 6, and 7 I have illustrated another type of plunger-operated valve, arranged for actuation by a trip device of the same general type as that shown in the figures already described, that is, a trip device in which the guard on the valve-carrying element actuates a finger and thereby throws a plunger-operating device into engagement with the plunger. In Figs. 5, 6, and 7 the movable element of the valve proper, designated by 40, has a rotary movement, instead of a lineal movement as in the former case, an arm 41 being provided to effect such movement. This arm or lever extends into a diagonal slot 42 in the plunger 13^a which is mounted for vertical reciprocation in the supporting frame 15^a. It will therefore be seen that upward movement of the plunger, to the position shown in Fig. 6 for example, will give the arm 41 a partial rotation, thereby opening the valve.

In Figs. 1 to 4 the fingers 30, 31, 32 and the sleeve 28 on which they are mounted are arranged to make only a partial revolution and to be returned to initial position by the spring 28^a. In the form illustrated in Figs. 5, 6, and 7, the device is completely rotatable, though a single actuation may not cause a complete rotation. In this form the fingers 43, 44, 45, 46, four in number in the present instance, are spaced equidistantly and are mounted on a member 47 which has an extension 48 provided with flat faces the same in number as the fingers and in register, so to speak, therewith. Below this extension is a flat-headed piston 49 mounted in a tubular carrier 50 between the forks of the stop arm 27^a and urged yieldingly against said extension 48 by a coil spring 51.

The parts being in the position shown in Fig. 5, with the car or train carrying the supporting frame 15 from right to left, the guard 22^a strikes the finger 44 and so brings the next finger, 45, up against the valve-operating plunger 13^a, lifting the latter and turning the valve-arm 41 as shown in Fig. 6. As the car moves on the rear guard, 23^a, carries finger 45 forward until it clears the same, whereupon the piston 49, co-operating with the part 48, rights the device and brings the parts to an operative position like that shown in Fig. 5, with two of the fingers in alinement with the stop-arm 27^a.

In both forms it is desirable to have the valve-operating parts light in weight so as

to lessen the inertia of the parts suddenly rotated by the guard and also to lighten the work performed by the signaling system in setting the stop-arm, and for this reason I prefer to make the fingers out of strong metal strips, for example spring steel, bent to the proper shape, as shown, and secure them to the sleeve 28 or member 47 in a convenient manner, as by bolts 52, 53. This construction also gives the fingers a certain amount of resiliency and diminishes the liability of breakage by the impact of or upon the guards and valve-operating plungers. It is also advantageous to reinforce at least one of the fingers, for example the middle finger, 31, in Figs. 1, 2, and 3, and all the fingers in Figs. 5, 6, and 7. For this purpose several leaf or blade springs 54 may be provided on the inside of the fingers, at each side thereof. In the form shown in Figs. 5, 6, and 7 the valve-operating device can, as previously stated, make a complete revolution, and can, in fact, be rotated indefinitely in either direction without injury. Such movement in the form shown in Figs. 1 to 4 would result in straining if not breaking the spring, and to prevent such occurrence due to inertia or meddlesome or mischievous persons a stop 55 is provided between the forks of the trip-arm 27, in position to engage finger 30 or 32 if the attempt is made to turn the device too far. This stop can be made yielding if desired by the addition of springs 56 on opposite sides.

Although the specific form of trip device illustrated in Figs. 1 to 4 is not shown in co-operation with a valve of the rotary type, as in Figs. 5, 6, and 7, it is clear that such trip device can be used with the latter type of valve. Likewise the trip device of Figs. 5, 6, and 7 can be used with the valve shown in Figs. 1 to 4.

It is to be understood that the invention is capable of embodiment in forms other than as herein specifically illustrated and described, without departure from its proper spirit and scope.

I claim:

1. In an automatic train controlling system, the combination of a movable controlling member mounted on a car or train, a guard in front of said member, and a track device provided with a movable member having a portion adapted to be deflected by said guard, and another portion for actuating the train controlling member by the deflecting movement of said movable member of the track device.

2. In an automatic train controlling system, the combination of a movable controlling member mounted on a car or train, a guard in front of said member, and a track device comprising a stop arm having a pivoted finger adapted to be deflected by said guard, and another finger connected with

the first for actuating the train controlling member by said deflecting movement.

3. In apparatus of the kind described, in combination, a reciprocatory controlling member adapted to be mounted on a car or train, a guard in front of the controlling member and immovable relatively thereto, and actuating means for said member, adapted to be mounted adjacent to the track on which the car or train is running, said means including an element adapted to be actuated by the guard and in turn to engage and actuate the reciprocatory controlling member.

4. In apparatus of the kind described, in combination, a supporting frame adapted to be mounted on a car or train, a reciprocatory controlling member associated with the frame, a guard carried by the frame in front of the controlling member and immovable relatively thereto, and actuating means for the controlling member, adapted to be mounted adjacent to the track on which the car or train is running, said means including an element adapted to be actuated by the guard and in turn to engage and actuate the reciprocatory controlling member.

5. In an automatic train controlling system, the combination of a train controlling member, and guards carried by the train in front and rear of said member, of a track device provided with a pivotally mounted member having a portion adapted to be deflected by the front guard, and another portion for actuating the train controlling member and adapted to be deflected to permit the passage of the rear guard.

6. In apparatus of the kind described, in combination, a movable controlling member adapted to be mounted on a car or train, front and rear guards in line with the controlling member and immovable relatively thereto, and actuating means for the controlling member, adapted to be mounted adjacent to the track on which the car or train is running, said means including an element movable by the guards to permit their passage and having a part brought by such movement into actuating engagement with the controlling member.

7. In apparatus of the kind described, in combination, a controlling valve adapted to be mounted on a car or train, a depending plunger associated with the valve, a depending guard in front of the plunger and immovable relatively thereto, and actuating means for the plunger, adapted to be mounted adjacent to the track on which the car or train is running, said means including an element movable by the guard by the passage thereof and having a part brought by such movement into actuating engagement with the plunger.

8. A trip device for automatic train stops, comprising, in combination, an element

- adapted to be mounted adjacent to a track and capable of vertical movement into juxtaposition to the path of a controlling member carried by a car or train on the track, a 5 device movably mounted on said element and having a plurality of fingers composed of sheet metal bent to proper form, and yielding means for normally maintaining the device in a given position relative to the 10 said element and with a finger in position to project into the path of the said controlling member when the said element is in its upper position.
9. A trip device for automatic train stops, 15 comprising, in combination, an arm adapted to be pivotally mounted adjacent to a track, a device pivotally mounted on the arm and having resilient radial fingers composed of sheet metal bent to a rounded form, and a 20 spring associated with said device to yieldingly oppose rotary movement thereof.
10. In an automatic train control system, the combination, with a train controlling member having a reciprocating plunger for 25 actuating the same, and a guard for protecting said plunger, of a track trip device having a portion adapted to be deflected by the guard and another portion for actuating said plunger.
11. In an automatic train control system, the combination with a train controlling member having a vertically reciprocating plunger for actuating the same, and a guard for protecting said plunger, of a track trip 30 device provided with a pivotally mounted member having a portion adapted to be deflected by the guard and another portion for actuating said plunger.
12. In an automatic train control system, the combination with a train controlling member having a reciprocating plunger for actuating the same, and guards at the front and rear of said plunger for protecting the same, of a track trip device provided with a pivotally mounted member having a finger 45 adapted to be deflected by the guard and another finger for actuating said plunger when the train is running in either direction.
13. In an automatic train controlling system, the combination with a train controlling member, and a projection carried by the train, of a track device provided with a movably mounted member having a portion adapted to be deflected by said projection, and 50 another portion for actuating the train controlling member by the deflecting movement of said movable member of the track device.
14. In an automatic train controlling system, the combination with a train controlling member carried by the train, and guards also carried by the train in front and rear of said member, of a track device provided with a pivotally mounted member having a portion adapted to be deflected by the front 55 guard, and another portion for actuating said train controlling member by said deflecting movement and adapted to be deflected by the rear guard.
